(57) **CLAIM**

The ornamental design for an ultrasonic probe, as shown and described.

DESCRIPTION

FIG. 1 is a perspective view of an ultrasonic probe, showing our new design;

FIG. 2 is a front side view of the ultrasonic probe;

FIG. 3 is a rear side view of the ultrasonic probe;

FIG. 4 is a top view of the ultrasonic probe;

FIG. 5 is a bottom view of the ultrasonic probe;

FIG. 6 is a right side view of the ultrasonic probe; and,

FIG. 7 is a left side view of the ultrasonic probe.

The broken lines in the drawings depict portions of the ultrasonic probe that form no part of the claimed design.
